UNITED STATES PATENT OFFICE.

WILLIAM H. CHAPMAN, OF PORTLAND, MAINE.

PROCESS AND APPARATUS FOR RECTIFYING ALTERNATING CURRENTS OF ELECTRICITY.

1,228,405.

Specification of Letters Patent.

Patented June 5, 1917.

Application filed September 29, 1915. Serial No. 53,193.

To all whom it may concern:

Be it known that I, WILLIAM H. CHAPMAN, of Portland, in the county of Cumberland and State of Maine, have invented certain new and useful Improvements in Processes and Apparatus for Rectifying Alternating Currents of Electricity, of which the following is a specification.

My invention relates to the production of constant polarity, high tension charges such as are required for X-ray work and for the commercial deposition of solids from smoke.

Hitherto the production of such charges has been attended with great difficulty. The well known influence machines of Holtz, Toepler and Wimshurst give excellent results for these uses if constructed on a large scale with a multiplicity of glass plates to gain the quantity and voltage required. But all of these machines are too fragile and too easily put out of commission by damp weather to be of extensive practical use for these purposes.

Transformers on the other hand produce charges that are very stable in all weather conditions and the transformers themselves are naturally rugged machines.

Many devices have therefore come into use to rectify the charges to be obtained from the transformers. All such devices hitherto constructed make use of a suitably timed carrier to pick off the positive side of the alternating wave from a conductor having alternating charges in it. The direct charge so obtained is always of lower voltage than the alternating charge from which it originated and the charges are of a pulsating character.

My invention is designed to provide means for multiplying up the voltage and of maintaining a uniform supply not subject to the pulsations of former rectifiers, thus making the current equivalent in its steadiness to that of a Wimshurst or a Toepler machine while having the quantity and stability characteristic of a transformer.

My invention consists essentially of delivering the negative ions of the alternating charge through an intervening air space onto the surface of thin insulating material which forms the dielectric element of a condenser.

The invention is based on the fact which I have discovered that if a sheet of paper is laid down onto the surface of a grounded body of conducting material like metal and a pointed conductor having an alternating

charge of several thousand volts be brought near the paper but separated therefrom by an intervening air space for an instant as it is in contact with the grounded conductor, the paper when moved from the surface of the conductor will show a very high negative charge of many times the voltage of the alternating charge. In fact a voltage of 100,000 volts may readily be produced in this manner by the use of an alternating charge of only 10,000 volts in the pointed conductor and the charge on the paper is invariably negative.

The explanation of this fact may be involved in the known fact that negative ions have a higher velocity than positive ions and more of them will therefore reach a given distant surface than of the positive ions during a single cycle of the alternating exciting charge.

Whatever the explanation may be, this principle has enabled me to construct an efficient producer of constant polarity high potential charges operative under all weather conditions.

My invention may best be understood by reference to the accompanying drawing in which I have illustrated diagrammatically several different mechanisms by which my invention may be carried out.

Referring to the drawing:

Figure 1 is a diagram showing the elements of my apparatus in simple form,

Fig. 2 shows an arrangement for collecting the positive electricity,

Fig. 3 shows an arrangement of conductors for effecting a uniform distribution of the charge over the surface of the paper,

Fig. 4 is an elevation of a machine using a disk in place of the band used in the other forms shown and

Fig. 5 is a section taken on the line $\alpha\alpha$ of Fig. 4.

In carrying out my invention I make use of a thin sheet of insulating material which is arranged to be brought repeatedly into contact or into close proximity to a conducting body discharging the alternating charge which is to be rectified onto the sheet through a comb pointed conductor whereby the air becomes ionized, the discharge taking place through a gaseous medium while the sheet is in contact with the conducting body. A negative charge of high potential will be generated on the surface of the sheet and is

collected in the usual manner after the sheet separates from the conducting body.

In the preferable form of my apparatus I make use of a pair of rolls of conducting material over which runs an endless band of paper or other insulating material.

Referring to the form shown in Fig. 1, *e* represents a continuous web of thin paper which may be .005 inch in thickness arranged to run over two metal rollers *a* and *b* like a belt over two pulleys.

Comb points or conductors *c* and *d* are located about 1 inch from the paper where it comes in contact with the rolls.

Comb points *f* and *g* are located near the paper at points where the paper is out of contact with the surface of the rolls.

The charge from the alternating generator *a'* is stepped up by means of a transformer of which *p* is the primary coil and *s* the secondary coil. The transformer is capable of maintaining a charge of 4000 volts or more on the combs *c* and *d*.

The rolls which are preferably grounded may be driven by any desired motive power and as the paper travels around it carries negative charges from *c* and *d* to *f* and *g* and the direction of movement is immaterial.

An exciting alternating voltage at *c* and *d* of 10,000 will easily maintain a constant direct voltage of 100,000 volts at *f* and *g* and the quantity of negative electricity thus supplied is proportional to the surface of the paper presented to the rolls per minute.

If it is desired to produce positive electricity this is easily accomplished by means of the apparatus shown in Fig. 2.

In this case the comb points *f* and *g* have extended surfaces or plates *f'* and *g'* located adjacent to the paper. The comb points *j* and *k* are located on the opposite side of the paper from the plates *f'* and *g'* and are connected with each other. The comb points *j* and *k* are grounded and the surfaces *f'* and *g'* which are charged with negative electricity induce positive charges in *j* and *k*. These positive charges in *j* and *k* are delivered to the paper and are collected by comb points *h* and *i*. In this case where positive electricity is to be collected it is necessary to have the rolls run in a pre-determined direction.

When a single comb is used to deliver the negative charge to the paper as it runs over the roll, the charge is greater on some sections than on others, due to the fact that the section of paper that happens to be passing under the points during the positive alternation is receiving little if any charge. A greater uniformity of charge is secured when two or more combs are used and placed some fraction of a cycle apart.

For example, suppose we are using a 60 cycle alternating current to supply the exciting charge to the combs and suppose the

paper is arranged to run at a speed of 360 inches per second.

Then the paper moves six inches during the time of one cycle of the A. C. charge and if a single comb is used every alternate space of three inches will receive a maximum negative charge and the intervening spaces a minimum charge. If now we place two combs three inches apart or nine inches apart measured along the peripheral surface of the roll, a greater uniformity of charge will be secured because every inch of the paper will, during the passage over the roll come under one or the other of the combs during a negative alternation of the exciting charge.

In Fig. 3 I show the arrangement of two combs *d* and *d'* for delivering the charge to the paper.

While the contact of the paper with the conductive surface is most desirable, my process may be carried out without this contact.

Instead of a belt I may use a paper disk and have it run in very close proximity to a solid grounded surface instead of being in actual contact with it as in the forms already shown.

In Figs. 4 and 5 I show an arrangement where a paper disk is made to rotate closely adjacent to a grounded metal plate.

Referring to Figs. 4 and 5, *l* represents a disk of paper or other insulating material mounted on a shaft *n* supported on suitable bearings and driven by a belt or other power. A grounded metal plate *m* of relatively large bulk as compared with the paper disk is set parallel to the disk and as close as possible to it without touching. A conductor *p'* having comb points is located on the opposite side of the disk from the grounded metal plate and connected with a source of alternating current preferably of 4,000 volts or more. A conductor *r* having comb points is presented to the disk at a point where it is not backed by any solid material. The conductors *r* and *p'* are supported by a standard *t* of insulated material.

The arrangement may be varied if desired by connecting the rolls to the alternating exciting charge while the combs *c* and *d* are connected with the ground. In this latter case the alternating charge on the rolls acts by induction on the grounded combs and causes them to deliver positive and negative ions to the intervening air.

The negative ions will arrive in greater abundance on the surface of the paper as is the case in the form shown in Fig. 1 and a negative charge will be collected on the collecting conductors as shown in dotted line in Fig. 1.

It is to be understood that while I have described specifically certain forms which my invention may take there are many other

forms which may be developed as the principle of the invention comes to be understood and developed for various purposes.

It is understood that in the drawings 5 similar letters of reference indicate similar parts.

I claim:

1. The process of rectifying charges from an alternating source of electricity which 10 consists of discharging said charges in the form of a glow discharge to a body of relatively thin non-conducting material backed by a body of conducting material whereby 15 ions of one sign are delivered upon said thin material, separating the materials from each other and finally collecting the resulting charge.

2. The process of rectifying charges from an alternating source of electricity which 20 consists of discharging said charges in the form of a glow discharge to a body of relatively thin non-conducting material backed by a body of conducting material whereby 25 ions of one sign are delivered upon said thin material separating the materials from each other and finally collecting the resulting charge from the thin material.

3. The process of rectifying charges from an alternating source of electricity which 30 consists of discharging said charges in the form of a glow discharge to a body of paper, backed by a body of metal, then separating the paper and metal and finally collecting the rectified charge from the paper.

35 4. In an apparatus for rectifying alternating charges of electricity the combination of a thin sheet of insulating material and a conducting body so movable with relation to each other that portions of the sheet will 40 repeatedly approach to a point adjacent to the conducting body and recede therefrom, a conductor having small discharging points or surfaces for delivering the alternating charge to the sheet while the same is adjacent to the conducting body and means for collecting the rectified charge from the sheet 45 after it has receded from the conducting body.

5. In an apparatus for rectifying alternating charges of electricity the combination of a thin sheet of insulating material and a conducting body so movable with relation to each other that portions of the sheet will repeatedly contact with the conducting body and recede therefrom, a conductor having small discharging points or

surfaces for delivering the alternate charge to the sheet while the same is in contact with the conducting body and means for collecting the rectified charge from the sheet 60 after it has receded from the conducting body.

6. In an apparatus for rectifying alternating charges of electricity the combination of a stationary conducting body, a movable sheet of insulating material rotating in such a position as to bring portions of its surface repeatedly adjacent to said conducting body, a conductor having small discharge points or surfaces for delivering the 70 alternating charge to the sheet while adjacent to the conducting body and means for collecting the rectified charge from the sheet when it is separated from the conducting body. 75

7. In an apparatus for rectifying alternating charges of electricity the combination of a pair of rolls of conducting material, a thin band of insulating material running over said rolls, a conductor having fine 80 points or surfaces for discharging the alternating charge onto said band while in contact with one of said rolls and means for collecting the rectified charge from said band while out of contact with said rolls. 85

8. In an apparatus for rectifying alternating charges of electricity the combination of a pair of metal rolls, a paper band running over said rolls, a conductor having fine points or surfaces for discharging the 90 alternating charge onto said band while in contact with one of said rolls and means for collecting the rectified charge from said band while out of contact with said rolls.

9. In an apparatus for rectifying alternating charges of electricity the combination of a pair of rolls of conducting material, a band of insulating material running over said rolls, a conductor having fine points or surfaces for discharging the alternating charge onto said band while in contact with one of said rolls, a collecting conductor for collecting the rectified charge from said band, a plate of conducting material connected with said collecting conductor 100 105 and positioned near said band and a grounded collecting conductor on the opposite side of said band from said plate.

In testimony whereof I have affixed my signature.

WILLIAM H. CHAPMAN.
